CLAIM

The ornamental design for an audio device with LCD display as shown and described.

DESCRIPTION

FIG. 1 is a top, front perspective view of an audio device with LCD display;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is an enlarged view of an encircled portion of the audio device with LCD display labeled 8 in FIG. 1.

The evenly-dashed broken lines shown in the drawings depict portions of the audio device with LCD display that form no part of the claimed design. The dash-dot-dot broken lines encircling portions of the audio device with LCD display in FIG. 1 illustrated in an enlargement in FIG. 8 form no part of the claimed design.

1 Claim, 8 Drawing Sheets
